DESIGN FOR A COMBINATION SALT AND PEPPER SHAKER SET

Howard L. Ross, New York, N. Y.

Application September 9, 1942, Serial No. 108,158

Term of patent 7 years

To all whom it may concern:

Be it known that I, Howard L. Ross, a citizen of the United States, residing at New York, in the county and State of New York, have invented a new, original, and ornamental Design for a Combination Salt and Pepper Shaker Set, of which the following is a specification, reference being had to the accompanying drawing, forming a part thereof.

In the drawing:

Fig. 1 is a side elevational view of a combination salt and pepper shaker set, showing my design; and

Fig. 2 is an end elevational view thereof.

Fig. 3 is a perspective view of the salt shaker element of the set; and

Fig. 4 is a perspective view of the pepper shaker element of the set.

I claim:

The ornamental design for a combination salt and pepper shaker set, substantially as shown.

HOWARD L. ROSS.
